(57) **CLAIM**

The ornamental design for a telescopic clothes hook, as shown and described.

DESCRIPTION

FIG. 1 is a front perspective view of a telescopic clothes hook, showing my new design;

FIG. 2 is a front view thereof;

FIG. 3 is a rear view thereof;

FIG. 4 is a left side view thereof;

FIG. 5 is a right side view thereof;

FIG. 6 is an enlarged top plan view thereof;

FIG. 7 is an enlarged bottom plan view thereof;

FIG. 8 is a partial enlarged view of the telescopic clothes hook taken from broken circle 8 in FIG. 1;

FIG. 9 is a partial enlarged view of the telescopic clothes hook taken from broken circle 9 in FIG. 1; and,

FIG. 10 is a partial enlarged view of the telescopic clothes hook taken from broken circle 10 in FIG. 1.

The broken lines in the drawings illustrate the portions of the telescopic clothes hook, which form no part of the claimed design.

The unevenly-spaced broken lines shown represent the boundaries of the partial enlarged views and form no part of the claimed design.
